SECURITY INTERCOMMUNICATING TELEPHONE SYSTEM.

1,180,559.

Specification of Letters Patent.

Patented Apr. 25, 1916.

Application filed December 9, 1912. Serial No. 735,621.

To all whom it may concern:

Be it known that I, WALLACE PFAU ANDRICK, a citizen of the United States, residing at Jamaica, in the county of Queens and State of New York, have invented a new and useful Secrecy Intercommunicating Telephone System, of which the following is a specification.

This invention relates to a secret or secrecy telephone system. A secrecy system already used in certain cases has comprised unit pairs of separate lines duplicated throughout the system, so that two stations in communication had merely a single pair of telephones which were disconnected from any other station. Another secrecy system hitherto used has involved the use of a relay which has had a number of contacts, and which system also involved the use of a dial with division contacts and intermediate contacts which were connected to a second relay which was thrown by the movement of the dial. Other systems hitherto used have imposed additional service requirements on the duty of the operators which is objectionable.

The main object of the present invention is to provide a system which is completely secret but in which there is no more manipulation of service on the part of the operator than is present in any ordinary intercommunicating telephone system.

A further object of the present invention is to provide a secrecy intercommunicating telephone system in which there is a minimum number of contacts both in the keys, and in the relay, and in which the circuits are generally direct and simple and not involved.

A further object of the present invention is to provide a system which is completely secret not only for the usual conditions of service but also for extraordinary conditions which arise only occasionally by chance.

A still further object of the present invention is to provide a system which is simple, cheap to construct and to install and durable.

With these objects in view the invention consists in the improved secrecy telephone system as hereinafter set forth and claimed.

In the drawings:—Figure 1 is a diagrammatic view showing a complete system and all the circuits thereof, as embodying the

invention. Fig. 2 is a sectional view showing a mechanical detail. Fig. 3 is a fragmentary view showing one of the station keys and the switch-hook and associated parts, the front casing being removed for the sake of clearness.

The present invention provides a system including any number of stations A, B, C, etc., of which three are illustrated in the drawing. The instruments include the usual transmitter 1, receiver 2, and a call bell or buzzer 3 which rings by a direct current. There is also one relay 4 with three contacts. There is also in each instrument a group of manually controlled keys 5 or any suitable station selecting devices, the number of which will ordinarily be one less than the number of stations, each having two contacts. Each station also has a ringing key 6 with two contacts, one which is made and one which is broken by either movement of the key. Also at each station there is a switch hook 7 having two upper contacts which are broken and a lower contact which is completed when the receiver is on the hook. There is also resistances 8, 9, one having, say fifty ohms and the other perhaps 100 ohms of non-inductive resistance, as an example. Two batteries 10, 11, are provided in the system, one for the ringing circuits and one for the talking circuits.

The system is used like a non-secret or ordinary intercommunicating telephone, that is to say, any party takes his receiver off the hook displaces the station selecting key, and then presses the ringing key. The party called removes his receiver and talks. In the meantime any other person of the system, pressing a key to call either of the communicating parties, can not complete any circuit which will affect the stations connected. In other words, he will not complete any ringing circuit or talking circuit with either of these two stations. The fact that he does not hear any buzzer induction effect shows that he is on a busy line, for he would hear the effect of the ring in case he called a party who is not busy in a normal way. Another indication would be provided by his own home relay which normally gives a certain click, but which does not give any click when the busy wire is called. This relay, as described, is characteristic of this

secret system, and has no counterpart in any other secret system.

In the event that A tried to call C while B is calling C then both A and B would be 5 put on C's circuit, and all can talk together, but this contingency is dependent on the mere chance that A happens to ring at the precise instant after B has rung C, and before C responds. In the meantime A has 10 rung C's buzzer and B who is listening will hear this and be advised that another party is in a position to hear. Thus B is advised of the possibility of the secrecy being interfered with and can call C again later. The 15 same would be true if under the same circumstances A tried to call B while C was calling B.

Any station in order to get a connection must necessarily ring the buzzer at that station, so that it is not possible to get in on 20 the line without having given an indication which might be investigated. Furthermore, if an attempt is made to leave the receiver off the hook permanently, that station can- 25 not be called and this fact will of course quickly lead to an investigation, so that it is not possible for any person either to listen in from time to time by taking a receiver off the hook at intervals, nor is it possible 30 to listen in by leaving the receiver off the hook all the time after having given a signal and not responded to the answer or not hung up after actually talking without the fact soon becoming known.

35 The present system operates broadly on the principle of having to ring before it is possible to get a telephone connection, the ringing operating the relay at the calling station that establishes the telephone cir- 40 cuit.

There will be a pair of wires for each station of the system, these wires running common to all the stations. There are also 45 four extra wires of which two are connected with a talking battery and the other two to a ringing battery. Three stations are shown of a five station system, there being four keys at each station necessary to call the outer four stations of the system. An ex- 50 tra pair of wires has been illustrated indicating the fact that extra wires and stations may be added, it being merely necessary to add an extra key and connections to the extra pair of wires.

55 When any station, for instance station A calls another station, for example C, A will of course remove the receiver from the hook, and displace the station C key. A's ringing key will also be pressed to move the blade 60 upward. Current flows from the negative pole of battery 10 through wire l^1 , wires l^2 , l^3 , relay magnet 4, wire l^4 , wire l^5 , contact l^6 , wire l^7 , contact l^8 , wire l^9 , cable wire c^1 , wire l^{10} , contact l^{11} , buzzer 3, wire 65 l^{12} , back to the battery. It will be observed

that this circuit includes the magnet 4 of A's relay, and the buzzer 3 of C's station.

The energizing of relay 4 at station A has an initial effect of allowing some current to flow through a slightly changed circuit, so that C's buzzer may ring with the full available strength of the battery. This prevents possibility of failure to ring by reason of the resistance and reactance of the relay. A low reactance shunt is established 75 across the relay coil from wire l^4 by means of the contact m^1 , wire m^2 , resistance 8, wire m^3 to the circuit wire l^3 . By putting the low resistance 8 in shunt with the relay magnet 4, there is of course a double path 80 provided and the low reactance leg insures sufficient current. At the same time the resistance 8 insures a slight potential difference across the relay magnet 4 to keep it energized enough to hold its armature. It 85 is to be particularly understood that the impedance of the relay magnet is the main source of difficulty because of the pulsating current required in the buzzer. The resistance 8 is a non-inductive resistance, and 90 may be comparatively high in ohmic value, and still give the effects just described.

It may be assumed that A will now release his ringing key 6, but a circuit has already 95 been established maintaining the relay magnet 4 energized, so that this energization continues notwithstanding the release of the ringing key 6. This circuit is as follows: battery 10, wire l^1 , wire l^2 , wire l^3 , relay magnet 4, wire l^4 , contact m^1 , large ohmic resistance 100 9, and contact o^1 hereinafter described, which is closed by the removal of A's receiver from the switch book, wire o^2 , back to positive battery. It will be observed that this circuit does not include the ringing key, so that the 105 circuit continues regardless of the release of the ringing key. The ringing is now complete and the matter of getting a current for C's buzzer is of course of no further interest. The only matter of interest now is maintaining the relay magnet 4 sufficiently energized to hold its armature, and this will be 110 done through the large ohmic resistance 9 in series with the relay magnet 4. The ohmic resistance 8 is of sufficient magnitude to insure sufficient potential across the relay to prevent the release of the relay armature notwithstanding the interposition of the high resistance 9, the line cable to and the buzzer 115 at the called station having by this time been cut out of the circuit by the release of the ringing key at the calling station. C removes the receiver from the hook and talking circuits are established as follows:— 120 talking negative battery 11, wire p^1 , wire p^2 , through the usual retardation coil R, wire p^3 , transmitter 1, and receiver 2 of station A, switch hook, wire p^4 , coil R, and wire p^5 to positive battery. This circuit produces 125 the usual potential fluctuations across the 130

receiver and transmitter, due to the changing resistances of this part of the circuit, and these voice currents are impressed on the line to station C through the following circuit: wire q^1 , contact q^2 , wire q^3 , contact q^4 , wire q^5 , cable wire c^1 , wire l^6 , contact l^8 , wire l^7 , lower spring blade q^7 , wire q^8 , contact q^9 , wire q^{10} , the switch hook, 7 to the other side of the telephone instruments at station A. It will be observed that since this circuit includes both the receiver and transmitter at station C which are further- 15 more bridged across the battery through retardation coils, the telephone circuit is complete for conversation in both directions. Of course the same operations are gone through in the same way when C calls A, or 20 B calls C, or any other combination of the system.

Consideration will now be given more particularly to the secrecy features by which any station is prevented from cutting in on 25 a busy line and hearing the conversation or taking part in it.

When the communication is concluded it is of course necessary to restore the circuits to their original normal condition, because 30 since A's relay has been operated by calling C it is evidently in condition to either call or listen on some other station after getting through with C. It will be understood that communication could not have been had 35 with C in the first instance, without actually calling C, but after the relay has been operated as described, circuits for possible communication might evidently be had with some other station without actually calling 40 that station, unless means were provided to prevent this. This is accomplished as follows: Assuming that C hangs up his receiver, and A for any reason may or may not restore the key for station C, it may be assumed for example that he displaces another 45 key, for example that for station B. This will not put him in communication with B through the energized relay 4 already described, because he is obliged to displace the 50 station B key and by this the relay 4 is restored to normal and natural circuit conditions already described.

When any station key is displaced, for example that for station B, even without A's 55 placing his receiver back on the hook, the contact o^1 is momentarily broken as herein-after described, and as the entire current for maintaining the relay 4 energized flows through this contact it is evident that the 60 relay releases its armature the instant that A manipulates any key. In other words, the circuits are restored to normal condition. A cannot then get B by any other method, except by definitely calling B, in 65 which case B will respond in the usual way.

If already busy B cannot be either called or talked to since the ringing circuit is open when the receiver is off the switch-hook and for which reason the relay at the calling station can not be energized to complete the 70 talking circuits.

It is an important principle of the present invention that the contact o^1 is broken under certain determined conditions, that is, when the receiver is hung up and also when 75 any station key is moved or displaced in either direction. Referring now to Figs. 2 and 3, a construction is shown similar to that disclosed in U. S. Letters Patent No. 1,081,712, granted Dec. 16, 1913, which discloses a construction whereby this result is obtained and comprises broadly a reciprocating link 13 which is connected at one end to a pivoted switch-hook 13' upon which the receiver normally hangs. The link 13 is 80 connected by means of a lost motion connection with a universal detent bar 14 having the ends thereof bent inwardly to form ears by which the detent bar is pivoted to the casting as at 14'. This bar constitutes the 85 detent for positively maintaining each of the station keys in either of its displaced positions, and it may be here stated that in Fig. 2, two sets of contact blades of two of the 90 station keys 5 are arranged one above the other, so that the set of blades corresponding to one station will be closed when the station key is depressed, and the other when the station key is moved in the opposite direction. Each key comprises a disk-like body 95 13 having two notches 16 therein in which the universal detent bar 14 falls when the key is in either of its depressed positions to hold it in such position against the tension 100 of the contact blades. When the detent bar 105 is lifted by the depression of the switch-hook, the keys will therefore return to their normal or open position under the tension of the contact-blades. Arranged at one end of the series of station keys 5, are two contact 110 springs 17 and 18, which have heretofore been referred to as the contact o^1 . These contact springs are normally closed and are moved to their open position by the engagement of the contact springs 17 with an insulated bushing 19 carried by the link 13. Upon downward movement of the link, due to the hanging up of the receiver, the contact 115 spring 17 will be forced out of engagement with the contact spring 18 and hence the contact o^1 will be opened. The contact will also be opened when any of the station keys are moved from their displaced position to their normal position by the operator, since the detent bar 14 will be moved upwardly 120 out of the notch 16 and hence its other end which is connected to the link 13, will move the link 13 and the insulated bushing 19 125 downward to open the contacts.

In the event that an attempt is made to 130

come in on a telephone circuit by the expedient of holding one key depressed after having concluded a regular conversation with that station, and at the same time pressing another key to another station the secrecy feature is still preserved because on account of the fact that bar 14 is a universal bar and coöperates as described with the keys, the contact α^1 is bound to be broken in any case. The expedient just mentioned will not serve to secretly gain telephonic communication. The only connection which can be established will be a new call to such station and by the use of the calling current as already described.

What is claimed is:—

1. In a secrecy intercommunicating telephone system, a plurality of stations each having a transmitter, receiver, signal, switch hook, and keys for the other stations, talking circuits interconnecting said stations, a common battery for supplying talking current to all of said talking circuits, and a relay at each station in the circuit of the signaling current to any station called, said relay having a contact by which talking circuits from such station to other stations can be exclusively established.

2. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay having a contact by which talking circuits from such station to other stations can be exclusively established, and means for maintaining said talking circuits completed after the termination of the signaling current.

3. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay having a contact by which talking circuits from such station to other stations can be exclusively established, and means for maintaining said relay operated after termination of the signaling current.

4. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay hav-

ing a contact by which talking circuits from such station to other stations can be exclusively established, and means for maintaining said last mentioned contact closed after the termination of the signaling current. 70

5. In a secrecy intercommunicating telephone system, a plurality of stations, each having a transmitter, a receiver, signal, switch hook, and keys for the other stations, a relay at each station in the circuit of the signaling current to any station called, said relay having a contact by which talking circuits from such station to other stations can be exclusively established, and a mechanically opened contact for breaking such talking circuits and means for opening said contact when any key is displaced or the receiver is placed on the hook at the calling station. 75

6. In a secrecy intercommunicating telephone system, a plurality of stations each having a transmitter, receiver, signal, switch hook, and keys for the other stations, a relay at each station in the circuit of the signaling current to any station called, said relay having a contact by which talking circuits from such station to other stations can be exclusively established, and a mechanical connection from the keys and also from the said switch hook for interrupting the talking circuits whenever any key is displaced or the receiver placed on the hook. 80

7. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay having a contact by which talking circuits from said station to other stations can be exclusively established, and a shunt circuit including a resistance automatically bridged across said relay when the latter is operated. 100

8. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay having a contact by which talking circuits from said station to other stations can be exclusively established, and a circuit for holding said relay when the latter is operated. 110

9. In a secrecy intercommunicating telephone system, a plurality of stations each having a transmitter, receiver, signal, switch hook, and keys for the other stations, talk- 120

ing circuits interconnecting said stations, a common battery for supplying talking current to all of said talking circuits, a relay at each station in the circuit of the signaling current to any station called, said relay having a contact by which talking circuits from such station to other stations can be exclusively established, and a contact closed by the removal of the receiver from the hook for maintaining said relay operated after it has been initially operated.

10. In a secrecy intercommunicating telephone system, a plurality of stations each having a transmitter, receiver, signal, switch hook, and keys for the other stations, talking circuits interconnecting said stations, a common battery for supplying talking current to all of said talking circuits, a relay at each station in the circuit of the signaling current to any station called, said relay having a contact by which talking circuits from such station to other stations can be exclusively established, and a branch circuit completed by the removal of the receiver from the hook and by the operation of the relay for maintaining said talking circuit closed after the initial operation of the relay.

11. In a secrecy intercommunicating telephone system, a plurality of stations each having a transmitter, receiver, signal, switch hook, and keys for the other stations, a relay to each station in the circuit of the signaling current to any station called, said relay having a contact by which talking circuits from such station to other stations can be exclusively established, and a low reactance shunt automatically bridged around said relay for the signaling current.

12. In a secrecy intercommunicating telephone system, a plurality of stations each having a transmitter, receiver, signal, switch hook, and keys for the other stations, and a relay to each station in the circuit of the signaling current to any station called, said relay having a contact by which talking circuits from such station to other stations can be exclusively established, a low reactance shunt automatically bridged around said relay for the signaling current, and a branch circuit for keeping the relay operated, said last mentioned branch circuit being interrupted by the displacement of any station key in any direction.

13. In a secrecy intercommunicating telephone system, a plurality of stations each having a transmitter, receiver, signal, switch hook, and keys for the other stations, a relay at each station in the circuit of the signaling current to any station called, said relay having a contact by which talking circuits from such station to other stations can be exclusively established, a branch circuit from said relay completed by said relay and by the removal of the receiver from the hook for maintaining said relay operated

after the termination of the signaling current, said last mentioned branch circuit being interrupted by the displacement of any station key in any direction at the calling station.

14. In a secrecy telephone system, a plurality of stations each having a transmitter, receiver, signal, a switch, and selective station connecting devices for the other stations, and a relay at each station in the circuit of the signaling current to a station called, said relay having a contact by which talking circuits from such station to other stations can be established independently of the station selective devices at the other stations.

15. In a secrecy telephone system, a plurality of stations each having a transmitter, receiver, signal, a switch, and selective station connecting devices for the other stations, a relay at each station in the circuit of the signaling current to a station called, said relay having a contact by which talking circuits from such station to other stations can be established independently of the station selective devices at the other stations, and means for maintaining said talking circuits completed after the termination of the signaling current.

16. In a secrecy telephone system, a plurality of stations each having a transmitter, receiver, signal, a switch, and selective station connecting devices for the other stations, a relay at each station in the circuit of the signaling current to a station called, said relay having a contact by which talking circuits from such station to other stations can be established independently of the station selective devices at the other stations, and means for maintaining said relay operated after termination of the signaling current.

17. In a secrecy telephone system, a plurality of stations each having a transmitter, receiver, signal, a switch, and selective station connecting devices for the other stations, a relay at each station in the circuit of the signaling current to a station called, said relay having a contact by which talking circuits from such station to other stations can be established independently of the station selective devices at the other stations, and means for maintaining said last mentioned contact closed after the termination of the signaling current.

18. In a secrecy telephone system, a plurality of stations each having a transmitter, a receiver, signal, a switch, and selective station connecting devices for the other stations, a relay at each station in the circuit of the signaling current to a station called, said relay having a contact by which talking circuits from such station to other stations can be established independently of the station selective devices at the other sta-

tions, and a mechanically opened contact for breaking such talking circuits when any key is displaced.

19. In a secrecy telephone system, a plurality of stations each having a transmitter, a receiver, signal, a switch, and selective station connecting devices for the other stations, a relay at each station in the circuit of the signaling current to a station called, said relay 10 having a contact by which talking circuits from such station to other stations can be established independently of the station selective devices at the other stations, and a mechanically opened contact for breaking 15 such talking circuits when any selective station connecting device is displaced or the said switch operated at the calling station.

20. In a secrecy telephone system, a plurality of stations each having a transmitter, 20 receiver, signal, a switch, and selective station connecting devices for the other stations, a relay in the circuit of the signaling current to a station called, said relay having a contact by which talking circuits from 25 such station to other stations can be established independently of the station selective devices at the other stations, means for maintaining said talking circuits completed after the termination of the signaling current, and means for interrupting the 30 circuit of said relay when any selective station connecting device is displaced at the calling station or the said switch operated.

21. In a secrecy telephone system, a plurality of stations each having a transmitter, 35 receiver, signal, a switch, and selective station connecting devices for the other stations, a relay at each station in the circuit of the signaling current to a station called, said relay 40 having a contact by which talking circuits from such station to other stations can be established, and a mechanical connection from the station selective devices and also from the said switch for interrupting 45 the talking circuits whenever any selective station connecting device is displaced or the said switch operated.

22. In a secrecy telephone system, a plurality of stations each having a transmitter, 50 receiver, signal, a switch, and selective station connecting devices for the other stations, a relay at each station in the circuit of the signaling current to a station called, said relay having a contact by which talking 55 circuits from said station to other stations can be established independently of the station selective devices at the other stations, and a shunt circuit including a resistance automatically bridged across said relay when 60 the latter is operated.

23. In a secrecy telephone system, a plurality of stations each having a transmitter,

receiver, signal, a switch, and selective station connecting devices for the other stations, a relay at each station in the circuit of 65 the signaling current to a station called, said relay having a contact by which talking circuits from said station to other stations can be established independently of the station selective devices at the other stations, and a circuit for holding said relay 70 when the latter is operated.

24. In a secrecy telephone system, a plurality of stations each having a transmitter, 75 receiver, signal, a switch, and selective station connecting devices for the other stations, a relay in the circuit of the signaling current to a station called, said relay having a contact by which talking circuits from 80 such station to other stations can be established, and a low reactance shunt automatically bridged around said relay for the signaling current.

25. In a secrecy telephone system, a plurality of stations each having a transmitter, 85 receiver, signal, a switch, and selective station connecting devices for the other stations, and a relay in the circuit of the signaling current to a station called, said relay having a contact by which talking circuits from such station to other stations can 90 be established, a low reactance shunt automatically bridged across said relay for the signaling current, and a branch circuit for keeping the relay operated, said last mentioned branch circuit being interrupted by 95 the displacement of any selective station connecting device in any direction.

26. In a secrecy telephone system, a plurality of stations each having a transmitter, 100 receiver, signal, a switch, and selective station connecting devices for the other stations, a relay in the circuit of the signaling current to a station called, said relay having a contact by which talking circuits from 105 such station to other stations can be established independently of the station selective devices at the other stations, a branch circuit from said relay completed by said relay and by the removal of the receiver from 110 the hook for maintaining said relay operated after the termination of the signaling current, said last mentioned branch circuit being interrupted by the displacement of 115 any selective station connecting device in any direction at the calling station.

In testimony whereof, I have hereunto set my hand, in the presence of two subscribing witnesses.
